UNITED STATES PATENT OFFICE.

HAL E. ERCANBRACK, OF ELGIN, ILLINOIS.

WRENCH.

SPECIFICATION forming part of Letters Patent No. 739,068, dated September 15, 1903.

Application filed May 4, 1903. Serial No. 155,463. (No model.)

To all whom it may concern:

Be it known that I, HAL E. ERCANBRACK, a citizen of the United States, and a resident of Elgin, in the county of Kane and State of Illinois, have invented a new and useful Improvement in Wrenches, of which the following is a specification.

My invention relates to an improvement in wrenches, and is particularly directed to wrenches comprising a fixed jaw and a movable jaw, with means for clamping the jaws in any desired adjustment with respect to each other.

The object of my invention is to provide certain improvements in the construction, form, and arrangement of the several parts whereby a very simple and strong wrench is obtained in which the movable jaw may be rapidly adjusted the required distance away from the stationary jaw and there rigidly locked.

A practical embodiment of my invention is represented in the accompanying drawings, in which—

25 Figure 1 represents the wrench in side elevation, a portion of the shank of the movable jaw being broken away to clearly show the spring for frictionally holding the locking-wedge in its advanced or locking position. 30 Fig. 2 is a rear elevation of the wrench. Fig. 3 is a similar view with the shank of the movable jaw and the wedge shown in section, the parts being shown in their released position. Fig. 4 is a similar view with the parts shown 35 in their locking position, and Fig. 5 is a view in perspective of the locking-wedge.

The fixed or stationary jaw of the wrench is denoted by 1, and it is provided with the usual straight shank 2.

40 Two handpieces 3 and 4 are secured to the front and back faces of the outer portion of the shank 2 of the fixed jaw to form a suitable handle for the wrench.

The back face of the shank 2 of the fixed 45 jaw is provided with a toothed rack 5, extending from the jaw to the handle.

The movable jaw is denoted by 6, and it is provided with a hollow shank 7, having a sliding engagement with the shank 2 of the 50 fixed jaw.

The inner wall of the shank 7 opposite the rack 5 is provided with a rack 8, extending

from the inner to the outer end of the shank, which rack is fitted to be engaged with and disengaged from the rack 5 on the shank of 55 the fixed jaw.

A sliding locking wedge-block 9 is arranged to draw the racks 5 and 8 into locking engagement with each other when slid in one direction and permits the racks to be disengaged from each other when slid in the reverse direction, which wedge-block is constructed and coacts with the shank of the movable jaw as follows: The front of the shank 7 is provided with an opening 10 there- 65 through communicating with the front face of the shank 2 of the stationary jaw. A recess 11 leads from the inner end of the opening 10 a short distance along the inner face of the front wall of the shank 7. A recess 70 12 leads outwardly from the outer end of the opening 10 along the inner face of the front wall of the said shank 7. This recess 12 starts at the opening 10 of substantially the same depth as the recess 11 and then 75 abruptly deepens to coact with one of the wedges on the locking wedge-block 9. The locking wedge-block 9 is provided with a wedge 13 on its inner end arranged to coact with the recess 11 and a wedge 14 at its outer 80 end arranged to coact with the recess 12. The wedge-block 9 is provided with a thin portion 15 beyond the wedge 13, which portion 15 is at all times located within the recess 11. The wedge-block 9 is further pro- 85 vided with a thin portion 16 between the wedge 14 and the body of the wedge-block, which thin portion is located in the narrow portion of the recess 12 when the wedge-block is in its released position. To lock the shank 90 7 of the movable jaw to the shank 2 of the fixed jaw, the wedge-block 9 is slid forward, thus forcing the wedge 13 into the recess 11 and the wedge 14 into the narrow part of the recess 12. When the wedge-block is in this 95 position, the racks 8 and 5 will be interlocked. To frictionally hold the wedge-block in its locking position, I provide a spring 17, which is located in a recess 18 in the inner side wall of the shank 7 opposite one side of the wedge-block 9. This spring 17 should be so located that it will not interfere with the shank 2 of the stationary jaw when the jaws are unlocked. The outer face of the wedge-block 100

9 may be provided with a roughened portion 19 for facilitating the operation of the wedge-block.

The wrench constructed as above set forth 5 is extremely simple and strong, the interlocking engagement between the shanks of the two jaws being an extended one. Furthermore, the movable jaw may be released or secured in position very quickly and easily.

10 What I claim is—

15 1. A wrench comprising a fixed jaw and its shank, a movable jaw and its shank embracing the fixed-jaw shank, the adjacent walls of the shanks on one side thereof having toothed racks, a wedge-block fitted to slide between the adjacent faces of the shanks on the other side thereof for bringing the racks into locking engagement and a spring engaging the side of the wedge-block for frictionally holding it in its locking position.

20 2. A wrench comprising a fixed jaw and its shank, a movable jaw and its shank embracing the fixed-jaw shank, the adjacent walls of the shanks on one side thereof having

toothed racks and a wedge-block having two 25 wedges arranged to be brought between the adjacent faces of the shanks on the other side from the racks for bringing the racks into locking engagement.

3. A wrench comprising a fixed jaw and its 30 shank, a movable jaw and its shank embracing the fixed-jaw shank, the adjacent walls of the shanks on one side thereof having toothed racks, the movable-jaw shank on the other side thereof having an opening and recesses leading from the inner and outer ends of the opening and a wedge-block located in the opening having wedges arranged to enter said recesses for bringing the racks into locking engagement.

40 In testimony that I claim the foregoing as my invention I have signed my name, in presence of two witnesses, this 29th day of April, 1903.

HAL E. ERCANBRACK.
